GARMENT RENOVATING APPARATUS

Edward F. Morken, Fort Wayne, Ind.

Application February 10, 1934, Serial No. 710,596

3 Claims.

This invention relates to improvements in garment renovating apparatus, and the object thereof is to provide an appliance for spreading out and supporting a garment while applying thereto a jet of steam in such manner as to cause it to be distended and revolved upon its support by force of the applied steam. Another object is to provide apparatus for steaming garments made of pile fabric in such manner that the steam is distributed with more or less force over the entire inner surface of the garment so as to cleanse the entire fabric body and raise the pile on the exterior thereof. Other objects and advantages of the invention will appear hereinafter.

In the usual practice of steaming velvet dresses, the garment is housed in a cabinet filled with steam, or, the dress is placed on a form or suspended while steam is applied at random from a nozzle that is manipulated by the operator. In the present instance, the garment is supported and steam applied in such manner that the garment is continuously rotated while distended by the force of steam introduced through a nozzle against the inner wall of the garment so that the pressure of the steam is distributed automatically more or less uniformly over the entire inner surface of the garment without need of manipulation by the operator.

An illustrative embodiment of the invention is shown in the accompanying drawing, in which:—

Fig. 1 is an elevation of the invention shown as applied to a garment;

Fig. 2 is a side elevation showing the invention applied to a garment the skirt of which is longer in the back than in the front;

Fig. 3 is a plan view of a skirt spreader and its guide, a steam nozzle being also included in the view; and

Fig. 4 is a detail perspective view of a preferred form of steam nozzle and its supporting foot.

The illustrative embodiment of the invention consists of a suspended dress hanger, a revolvable skirt spreader, a guide for the spreader, and a nozzle for applying steam to a garment that is suspended from the hanger and attached to the spreader.

The hanger

The hanger 1 is of the usual structure for suspending a dress from the shoulders and is attached to an overhead stationary support 2 by a cord connection 3 preferably provided with a swivel 4 so that when a garment 5 is suspended on the hanger and rotated upon its longitudinal

axis detrimental twisting of the cord connection is circumvented.

The spreader

The spreader consists of a hoop 6 and a hub 7 concentric therewith which is connected with the hoop by spokes 8. The hoop has attached thereto by means of individual flexible connectors 9 a series of fasteners 10 of any suitable character adapted for ready attachment to the hem of a garment 5 so that when applied to a garment suspended on the hanger the spreader is pendently supported substantially in horizontal position beneath the garment whereby the skirt thereof is held spread outwardly and stretched.

The guide

The guide consists of a floor base 11 provided with an upwardly extending post 12 which when the guide is in operating position projects loosely through the bore 13 of the hub 7. Preferably, the bore of the hub is sufficiently large as to permit freedom of axial turning and tilting movement of the spreader with respect to the guide post while attached to a garment suspended on the hanger.

The nozzle

The nozzle through which steam is applied to the garment preferably consists of a pipe 14 provided with an insulating handle 15 and has also attached thereto a cross-piece 16 constituting a foot that prevents the pipe from turning axially when the foot is positioned on the floor. The discharge end of the pipe has an upturned portion constituting a nozzle 17, and the opposite end of the pipe is connected to a source of steam supply under pressure by a flexible hose (not shown).

Operation

In using the apparatus, the hanger while attached to the stationary support by its connection is inserted through the neck of the garment so as to extend beneath the shoulders, thus suspending the garment. The spreader is positioned upon the guide which is aligned upon the floor beneath the stationary support, and the fasteners 10 are attached to the hem of the skirt so that the spreader is suspended therefrom at a point spaced above the floor thereby stretching the garment lengthwise. The nozzle is then positioned with its discharge end beneath the spreader and directed upon an incline at an acute angle toward the inner wall of the skirt. When steam is turned on through the pipe and expelled through the

nozzle, the garment becomes distended and also rotated by pressure of the steam thus ejected. While the nozzle is stationary and the garment revolves the impact of the steam is distributed automatically over the inner surface of the garment. The steam from the interior of the garment oozes through the fabric thereof causing its pile to stand out from the exterior surface while the entire fabric body is cleansed by the oozing steam.

When a garment 5' of the form shown in Fig. 2 is applied to the apparatus, the back of the skirt being longer than the front, the spreader is suspended accommodately upon more or less of an angle which is permitted because the bore of its hub is greater than the guide-post. In this instance when the steam is applied the spreader rotates upon the axis of the guide-post while the garment is held in longitudinal tension by the weight of the spreader as in the former instance.

In the preferred form of nozzle and support shown in Fig. 4, the steam pipe 14' and a stud 18 are secured in the opposite ends of a T connection 19 and the stud is adjustably secured in the foot 16' by a clamp screw 20. The nozzle 17' is secured in the side branch of the connection and its tip is flattened to form an elongated narrow discharge opening 21. The pipe 14' may be adjustably turned upon its axis relative to the foot by manipulating the screw so that the nozzle will be posed at the desired angle when the foot and the pipe rests upon the floor.

I claim:—

1. In a garment renovating apparatus, a stationary support, a hanger suspended from said support by a connection provided with a swivel, a spreader having a hoop and a concentric hub connected therewith by spokes and provided with an annular series of fasteners connected with the hoop at intervals by flexible connectors, a guide having a floor base provided with an upwardly extending post alined with said stationary sup-

port, said post extending loosely through the hub of the spreader, and a steam-ejecting nozzle disposed beneath the spreader and directed at an acute angle toward the inner surface of a garment when said garment is suspended from said hanger and connected at its bottom to said spreader by said fasteners so that when steam is ejected from the nozzle the garment is extended and rotated by the ejected steam.

2. In a garment renovating apparatus, a rotatably mounted hanger, a spreader having an outer annular series of fasteners connected therewith at spaced intervals and provided with a central hub, a guide-post disposed vertically in alinement with the axis of said hanger and extending loosely through the bore of said hub and upon which post said spreader has axial, tilting and turning movement, and a steam-ejecting nozzle positioned beneath the spreader and directed at an acute angle toward the inner surface of a garment when said garment is suspended from the hanger and said spreader is in position on the post and attached to said garment so that when steam is ejected from the nozzle the garment is thereby extended and rotated.

3. In a garment renovating apparatus, a garment hanger supported to have free turning movement upon a vertical axis, a garment spreader having a series of fasteners for attaching the spreader to the lower end of a garment suspended from said hanger, said spreader having a hub, a post disposed vertically in alinement with the axis of said hanger and extending through the bore of said hub, and a steam-ejecting nozzle disposed beneath the spreader arranged for applying a jet of steam at an acute angle against the inner surface of a garment when said garment is suspended between the hanger and spreader so that said garment is thereby extended and rotated while cleansed by the steam.
